UNITED STATES PATENT OFFICE.

OTIS B. MOYE, OF SOPERTON, GEORGIA.

MACHINE FOR BORING STUMPS.

No. 806,171.

Specification of Letters Patent.

Patented Dec. 5, 1905.

Application filed August 3, 1905. Serial No. 272,548.

To all whom it may concern:

Be it known that I, OTIS B. MOYE, a citizen of the United States, residing at Soperton, in the county of Montgomery and State of Georgia, have invented certain new and useful Improvements in Machines for Boring Stumps; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in apparatus for boring holes in stumps for the purpose of facilitating the removal of a stump by boring a hole through the tap-root and affording means whereby a fire built about the stump may be drawn through the aperture to expedite the burning of the same.

The invention consists, further, in an apparatus for boring holes below the surface of the ground in stumps for blasting or other purposes; and it consists in a suitable lever which is anchored at one end to a stump and adapted to carry a threaded socket in which a shaft-carrying auger has a bearing and so arranged that the auger may be held securely while a hole is being bored in the stump.

My invention comprises various details of construction and combinations and arrangements of parts, which will be hereinafter fully described and then specifically defined in the appended claims.

My invention is illustrated in the accompanying drawings, which, with the letters of reference marked thereon, form a part of this application, and in which—

Figure 1 is a perspective view showing the application of my invention. Fig. 2 is a vertical sectional view, and Fig. 3 is a detail view showing the means for holding the shaft-carrying socket.

Reference now being had to the details of the drawings by letter, A designates a lever which may be of any suitable length and is provided with an opening A' therein, and B 50 designates a chain which is anchored to said lever, preferably passing through an aperture transversely formed in the lever, and the ends of said chain are adapted to be passed about the circumference of a stump and hooked together in the manner shown in the drawings,

whereby one end of said lever may be securely held and anchored to the stump.

C designates a spherical socket member which may be made either of one or two pieces and provided with a central threaded aperture adapted to receive the threads upon a shaft E, having a crank-arm E' formed at one end. Said shaft E has a bit-socket G for the reception of a bit or auger H. In order to hold said socket member, through which the threaded shaft passes, in position, I provide a strap K, one end of which is hinged at K' in the side of the lever, and said strap is concaved to conform to the convexed or spherical circumference of said shaft-carrying member, and the free end of the strap is apertured to receive a bolt N, passing through said lever, and a thumb-nut O is provided to engage the end of said bolt to hold the free end of the strap against the lever and in engagement with said member G to hold the same in place. The opening A' in the lever A is of sufficient size to allow for the adjustment of the shaft at different angles, as will be readily understood.

The operation of my apparatus will be readily understood when considered in connection with the drawings forming a part of this application, and in applying the device the lever is placed flat upon the ground and the chain adjusted in the manner shown, the soil about the stump first being removed for a slight distance down to expose a portion of the tap-root into which it is desired to bore the hole. The lever being adjusted, the auger and the shaft are adjusted in position, as shown, and a diagonal hole may be easily and quickly bored through the tap-root, the auger being steadied by the operator resting his weight upon the lever, if necessary. The hole being bored, the auger may be removed and the lever detached, and the soil being removed from the opposite side of the tap-root where the aperture opens through the same means is provided whereby air for combustion purposes may be fed to a flame passing through the aperture, thereby rendering it an easy matter to burn off the tap-root, after which the superficial roots may be quickly burned and the stump removed from the ground.

Having thus fully described my invention, what I claim as new, and desire to secure by Letters Patent, is—

1. An apparatus for boring holes in stumps, &c., comprising a lever with an opening there-

in, which opening is adapted to permit a shaft to pass diagonally therethrough means for anchoring one end of said lever to a stump, a threaded shaft, a bit with auger connected thereto, a bearing member having a threaded aperture through which said shaft passes, and means for holding said bearing member frictionally against the marginal outline of said opening, as set forth.

- 10 2. An apparatus for boring holes in stumps, &c., comprising a lever with an opening therein, which opening is adapted to permit a shaft to pass diagonally therethrough means for anchoring one end of said lever to a stump, a threaded shaft, a bit with auger connected thereto, a spherical bearing member having a threaded aperture therein engaged by the threads of said shaft, a strap hinged at one end to the edge of said lever and concaved upon one side and engaging said spherical bearing member and designed to hold the same frictionally against the inclined marginal wall of said opening of the lever, as set forth.
- 15 3. An apparatus for boring holes in stumps,

&c., comprising a lever with an opening there- 25 in, which opening is adapted to permit a shaft to pass diagonally therethrough means for anchoring one end of said lever to a stump, a threaded shaft, a bit with auger connected thereto, a spherical bearing member having a 30 threaded aperture therein engaged by the threads of said shaft, a strap hinged at one end to the edge of said lever and concaved upon one side and engaging said spherical bearing member and designed to hold the same 35 frictionally against the inclined marginal wall of said opening of the lever, a bolt passing through said lever and engaging the free end of said strap, and a thumb-nut upon said bolt adapted to hold the strap against said bearing 40 member, as set forth.

In testimony whereof I hereunto affix my signature in the presence of two witnesses.

OTIS B. MOYE.
